C. BOOZE.
WALL PAPER.

No. 20,329.

Patented Nov. 18, 1890.

UNITED STATES PATENT OFFICE.

CHARLES BOOZE, OF BUFFALO, NEW YORK, ASSIGNEE TO M. H. BIRGE & SONS, OF SAME PLACE.

DESIGN FOR WALL-PAPER.

SPECIFICATION forming part of Design No. 20,329, dated November 18, 1890.

Application filed September 27, 1890. Serial No. 366,337. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

The leading feature of my design consists of a figure composed of flowers and leaves of the primrose arranged in a conventionalized manner and placed at regular distances upon a background of tinted paper of any desired 10 color. As represented in the accompanying photograph, the leaves forming the base of the figure are arranged in a horizontal scroll, and the center of the figure is composed of leaves branching upwardly and outwardly from the scroll or base. A primrose in full 20 bloom is arranged at the top of the figure and on one side of the figure, and a flower in blossom is arranged between the leaves forming the base or scroll and the center of the figure. 25

What I claim is—

The design for wall-paper herein shown and described.

Witness my hand this 13th day of September, 1890.

CHARLES BOOZE.
